AIRPLANE PROPELLER

Erle Martin, Hartford, Conn., assignor to United Aircraft Corporation, East Hartford, Conn., a corporation of Delaware

Application May 7, 1934, Serial No. 724,418

8 Claims. (Cl. 29—156.8)

Airplane propellers may be made hollow and of metal and the present invention is particularly adapted to such propellers although in all of its aspects it may not be confined thereto.

Such airplane propellers are subjected to large stresses when operated. A purpose of the present invention is to secure a better distribution of such stresses and to reinforce the parts particularly affected. The invention also has to do with mounting blades of airplane propellers in their hubs. Other phases of the invention are important in the manufacture of the blades.

In the accompanying drawings Figure 1 is a plan view of an airplane hub carrying two propeller blades which are illustrated broken off, the right hand portion of the figure being illustrated in horizontal section. Fig. 2 is a transverse vertical section on the line 2—2 of Fig. 1. Figure 3 is a schematic illustration showing a furnace and a die press used in the within described process of manufacturing airplane propellers. Figure 4 is a vertical sectional view on an enlarged scale of the front end of the die press illustrated in Figure 3 showing a propeller blank and reinforcing sleeve in position in the dies. Figure 5 is a vertical sectional view similar to Figure 4, illustrating a subsequent stage in the operation of the die press.

In the drawings is illustrated a shaft 10 which may be rotated by the motor or in any desired way. Mounted on the shaft 10 is a split hub consisting of the inner section 11 and the outer section 12 held together by means of the bolts 13 passing through lugs 14 carried by the two sections of the hub 11 and 12. The hub sections comprise inner thimble members 15 which may closely surround the shaft 10. On their outer surfaces the hub sections 11 and 12 include semi-circular slots 16 which cooperate with each other to form circular cavities for holding the propeller blades 17. The propeller blades 17 illustrated consist of a hollow shell of metal, such as steel for instance, which tapers in thickness from the butt end toward the tip (not shown). At the hub end the blade is circular in cross section. It will be understood that the outer portion of the blade not here illustrated may be of any usual or desired airfoil form.

Within the butt end of the propeller blade 17 is a sleeve or thimble 18, preferably of such a metal as steel which, as illustrated, tapers in thickness in the same direction as the wall of the blade and has at its butt end an outwardly extending flange 19 which overlies and is in close contact with the out-turned flange 20 at the butt end of the blade 17. The outer face 21 of the flange 19 may be

carefully machined smooth to rest upon and engage the correspondingly prepared seat 22 in the circular channel 16 of the hub members 11 and 12. It will be noted that the flange 20 of the blade 17 extends at substantially right angles to the main body of the blade 17 but on its outer side instead of having a sharp right angle, it is formed with an easy curve indicated at 23. Likewise the turn at the inner edge of the flange 20, indicated at 24, is an easy curve corresponding to the contour of the sleeve 18. Resting against the curved portion 23 of the flange 20 of the blade 17 is a thrust ring 25 having an inner face 26 curved on a relatively large radius so as to have a relatively large surface seating on the flange 20. The curve 15 at 26 is preferably not identical with the curve at 23 and may be on a smaller radius so that there may be freedom to allow the parts under deforming forces to adjust themselves to fit. The thrust ring 25 as clearly indicated in Fig. 2, consists of 20 two semi-circular members whose added circumference is slightly less than the outer circumference of the blank of the propeller blade 17. The propeller blade 17, carrying the sleeve 18, may be placed between the expanded hub members 11 25 and 12 with the seat 21 of the flange 19 in position to rest upon the seat 22. The sections of the thrust ring 25 may then be placed in position about the base end of the blade 17 and arranged 30 against the outer surface 23 of the flange 20. The sections 11 and 12 of the hub may then be forced together so that the thrust ring 25 is engaged by the circumference 27 of the cavity 16 and also by the inwardly extending lip 28. The bolts 13 may then be put in place and the sections 11 and 12 35 of the hub drawn tightly together and the thrust ring 25 will thus be forced against the flange 20 of the propeller on an adjustable broad surface and so will force the flange 19 tightly against its seat 22. The propeller blades 17 will thus be 40 mounted by their respective flanges in the hub. It will be noted that the outer circumferential surface of the flange 20 is held out of contact with the surface 27 of the cavity 16 and the lip 28 does not make contact with the surface of the propeller 45 blade 17.

The thrust ring 25 may be made of steel and, as formed, permits the use of a very large fillet between the shank of the blade 17 and the flange 20 and thus greatly improves the distribution of the 50 loads at this point. Although the surface 23 of the propeller blade at the flange end and the coacting surface 26 of the thrust ring are preferably of slightly different radii and might theoretically have only a line contact, the surface deflection at

these points is great enough so that a substantial surface is in contact and the loads are not transmitted through a line contact.

In order to insure that the separation points 29 between the ends of the halves of the thrust ring 25 do not coincide with the split between the two sections of the hub 11 and 12, in one or both of the halves of the thrust ring 25 there may be provided one or more holes or slots 30 to be engaged 10 by positioning pin 31 placed in a corresponding slot 32 formed in one of the hub sections 11 adjacent its edge. Since the slot 30 in the thrust ring 25 is placed at some distance from the end of the sections such assembly insures the divisions 29 being not in registry with the line joining the two halves 11 and 12 of the hub.

The manufacture of the propeller blade may be by any suitable process and may follow a process such as is described in application Ser. No. 20 36 679,133 filed July 5, 1933 by John Squires and may commence with a hollow metal tube. This hollow metal tube may be tapered from butt end to tip. In order to insure the blade being as light as possible with the necessary strength it is desirable that the tube be of as thin metal as possible. The operations to which the tube is submitted in the manufacture require that the inner diameter at the hub be kept substantially as large as any other point. It is obvious then that 30 the tube cannot be thickened inwardly at the hub end. Likewise the hub end cannot be made very thick outwardly. By beginning with a thick tube much material will be wasted, it may be nearly impossible to satisfactorily form the flange 35 28 and the possibility of procuring a tube of metal of uniform condition will be materially limited. Moreover, a very thick portion of the tube will be very difficult to handle and properly heat treat. Nevertheless since the stresses on the blades induced by the whirling of the propeller in operation, 40 are of very large magnitude some means of reinforcing the hub end of the hollow blade are desirable. This is conveniently accomplished by providing the internal sleeve 18 which itself is 45 tapered so as to provide the necessary reinforcing support progressively along the hub end of the blade. The blade is thus strengthened and the load distributed. Additional reinforcing metal on the surface of the shank of the blade may be 50 undesirable as adding additional weight to the propeller because of the larger diameter on which the metal would occur. In manufacture the hollow tube 17' to form the propeller blade 17 may be provided with a suitable flange and brought into 55 the proper condition and then heated to a forging heat in a suitable furnace 32, a heat of from 1200° F. to 1700° F. being satisfactory for one material mentioned in the Squires application referred to. The tube may then be inserted into 60 dies to deform the outer portion of the blade to proper airfoil shape. In the shaping operation the blank 17' is heated in the furnace 32 to a forging temperature, that is, a temperature at 65 which the material of the blank may be deformed to the extent required without creating undue stresses in the material. When the blank is at the proper temperature, it is removed from the furnace and inserted in the die press 34, the press being in the position illustrated in Figure 70 3 with the upper and lower die members 36 and 38 respectively separated to their fullest extent. The blank is inserted through a ring member 40 supported upon the base of the die press and the blank is supported by the ring member so that it 75 is out of contact with both die members. Imme-

dately after the blank is placed in the ring member 40, the sleeve 18 is inserted in place in the butt end of the blank and the breech member 42 is closed and locked in position against the adjacent face of the sleeve member thus rigidly securing the tube blank and sleeve member in the ring 40. As soon as the breech member 42 has been located in the closed position, illustrated in Figure 5, the upper and lower die members 36 and 38 are brought together to form the tube 10 blank 17' to the proper air foil contour. As explained above the water cooled die elements 36 and 38 quickly remove the heat from all of the thin portions of the blade in contact with the die members, but the mounting ring 40 is not 15 capable of removing the heat from the thick root portion of the blade as rapidly as the heat is removed from the thinner portions by the water cooled die members. Under these conditions the insertion of the cold sleeve member 18 in the root 20 or base end of the blade during the chilling process materially assists in providing all portions of the blade with the same temperature since the sleeve member removes the heat from the inside of the thickened base portion at the same time 25 that the ring member 40 and the adjacent end portions of the die members 36 and 38 are removing the heat from the thickened base portion through the exterior surface thereof. The condition thus described is clearly illustrated in Figure 5. The die members 36 and 38 are desirably 30 provided with suitable cooling means such as the passages 44 through which a cooling liquid may be forced to carry away the heat transferred to the die members by the hot blank 17'. By means 35 of this arrangement, the hot blank is quenched by the die to provide a heat treatment commonly referred to as chilling. In the above described shaping operation the inner or hub end of the blade is not deformed, but it does undergo a heat 40 treatment from its contact with the die member and ring 40. It is desirable that the metal of the propeller blade be all chilled or cooled to about the same metallurgical effect. Since the hub 45 end of the blade blank is thicker than the rest of the blade this portion will contain more heat units and will not be cooled as rapidly as the inner portions of the blade in contact with the die. Under these conditions, a uniform heat treatment of the entire blade may be conveniently 50 accomplished by thrusting the sleeve 18 while cold into the heated hollow end of the blank 17' while in the dies for forming the outer portion of the blade. The putting in place of the cold sleeve 55 18 chills, from the inner side, the hub end of the blade 17 the outer side of which may be cooled by contact with the dies, and the flange 19, by contact with the flange 20, similarly chills or cools the flange 20. This procedure greatly improves 60 the heat treatment of the blade end over any heat treatment that could be given to a solid hub end of equal strength, and this is done without actually increasing the thickness of the blade itself and, at the same time, reinforces the 65 blade at the hub end. The length of the sleeve 18 and its proportions may vary in accordance 70 with the desires of the designer or the results to be obtained.

The sleeve 18 may be made somewhat larger in 75 diameter than the internal diameter of the hub end of the blade 17 when cold. When heated to the forging temperature described above the blade 17 expands allowing the sleeve to be inserted and the cooling causes the sleeve 18 to have a shrink fit in the hub end of the blade. It 75

appears, however, that there is a slight movement between the blade and the insert during operation and this movement absorbs energy and dissipates, in the form of heat, the energy which 5 might otherwise cause undesirable stresses in the blade.

The invention has to do with the hub end of the propeller blade and the character of the outer portion of the blade is not of great importance to most phases of the invention. While the outer portion of the blade may be hollow some phases of the invention may be applied to a solid blade or to one which is substantially solid except for the hub end which may be hollow for 10 a portion of the blade.

While there has been illustrated and described a suitable mechanical embodiment of a propeller blade constructed according to the idea of the invention and a suitable process for manufacturing the improved blade, it is to be understood that the invention is not limited to the construction so illustrated and described nor to the particular steps of the process in the order 20 hereinabove set forth but that such changes in the size, shape, and arrangement of parts and in the order of the steps of the process and in the various steps themselves may be resorted to as come within the scope of the appended claims.

Having described the invention so that others 30 skilled in the art may clearly understand the same, what it is desired to secure by Letters Patent is as follows.

I claim as my invention:

1. The method of heat treating a metal propeller blade blank having a thickened hollow end comprising heating the blank to a tempering heat, and inserting in the thickened hollow end a cold steel sleeve and cooling the surface of the blank in dies.

40 2. The method of heat treating a metal propeller blade blank having a thickened hollow end with an outwardly extending flange comprising heating the blank to a forging heat, inserting in the end a cold steel sleeve having an outwardly extending flange so that the sleeve comes into close contact with and cools the contacting portion of the blank and the flange on the sleeve comes into close contact with and cools the flange on the blank, and cooling the surface of 50 the blank in dies.

3. A metal propeller blade having a hollow hub with an outwardly extending flange and a portion adjacent the flange of varying wall thickness progressively decreasing away from the flange, and 55 a reinforcing steel sleeve permanently secured within the end of the propeller blade by a shrink fit and having at its end an outwardly extending flange in contact with the propeller flange and a body of exterior diameter approximately 60 equal to the inside diameter of the propeller and having a wall of varying thickness progressively decreasing away from the flange.

4. An airplane propeller blade, an outwardly extending flange at the hub end so formed that 65 the junction between blade and flange on its

outer face is a curve of relatively large diameter, a split thrust ring surrounding the blade and having a face of corresponding curve engaging the junction of flange and blade and having a relatively flat outer face, a hub for supporting the 5 blade having a seat for supporting the end of the blade, and a member engaging the flat face of the thrust ring and adapted by means of a radial movement to put pressure on the thrust ring to tend to hold the blade toward its seat. 10

5. An airplane propeller blade having a hollow hub end, an outwardly extending flange at the hub end having a flat face at the base of the blade and having a junction between the blade and flange in a curve of relatively large diameter, a 15 reinforcing tubular insert in the blade and having an outwardly extending flange engaging the blade flange and having a flat face, a split thrust ring surrounding the blade and having a correspondingly formed face engaging the junction of 20 the flange and blade and a flat face toward the blade tip, a split hub having a seat against which rests the flat face of the flange of the insert and a seat for the flat face of the thrust ring and means for contracting the split hub in a direction radial of the propeller blade so as to cause 25 the thrust ring to force the flat face of the insert firmly against its seat.

6. The method of manufacturing a metal propeller blade which comprises forming a blank 30 having a hollow thickened end portion with an outwardly extending flange, heating the blank to a tempering heat, rapidly removing the heat from the blank by placing the same in contact with a die, and at the same time removing heat 35 from the thickened end portion by inserting a cold, metal sleeve in the end portion in contact with its inner surface, and leaving the sleeve in the hollow end portion to act as a reinforcing member for the flanged end of the blade. 40

7. The method of manufacturing a metal propeller blade which comprises, forming a blank having a hollow thickened end portion with an outwardly extending flange, heating the blank to a forging temperature, inserting the blank in a 45 set of cold blade forming dies to form the blade and at the same time quench the blade material by rapidly removing the heat therefrom, and simultaneously removing heat from the thickened end portion of the blank by inserting a cold metal 50 sleeve in the end portion in contact with its inner surface, and leaving the sleeve in the hollow end portion of the blank to act as a reinforcing member for the flanged end portion of the blade.

8. The method of heat-treating a metal propeller blade blank having a hollow end which comprises, heating the blank to a heat-treating temperature, removing heat from the outside of said blade blank by placing it in contact with a solid cooling medium and simultaneously removing heat from the inside of the hollow end of said blade blank by placing a cold sleeve in contact with the inside of said hollow end. 55 60

ERLE MARTIN.
